UNITED STATES PATENT OFFICE.

GUSTAVE DELAGE, OF ISSY-LES-MOULINEAUX, FRANCE, ASSIGNOR TO SOCIETE ANONYME DES ETABLISSEMENTS NIEUPORT, OF ISSY-LES-MOULINEAUX, FRANCE.

AEROPLANE.

1,331,807.

Specification of Letters Patent. Patented Feb. 24, 1920.

Application filed August 7, 1917. Serial No. 184,967.

To all whom it may concern:

Be it known that I, GUSTAVE DELAGE, a citizen of the French Republic, and residing at 46 Boulevard du Point du Jour, Issy-les-Moulineaux, Seine, France, have invented certain new and useful Improvements in Aeroplanes, of which the following is a specification.

This invention has for its object to provide an improved aeroplane.

The improved aeroplane is of the triplane type with three very narrow planes comprising a single longitudinal, and attached to the three apices of a triangle formed by the uprights that connect the planes together.

The manner in which this invention is to be performed will now be more particularly described in the accompanying drawings which illustrate by way of example a constructional form of the improved aeroplane.

In these drawings:—

Figure 1 is a longitudinal side elevation of the aeroplane; and

Fig. 2 is a perspective view of the general arrangement of the aeroplane.

In the improved aeroplane the three planes 1, 2, 3 are attached to the three apices of triangular frames constituted by uprights 4, 5, 6 which serve at the same time to connect the said planes together.

These planes are very narrow; they have each only one longitudinal at the point where they are attached to the uprights.

They are staggered in such a manner that the top plane 3 is set forwardly of the bottom plane 1, and that the latter is set forwardly of the middle plane 2, so that the latter forms a tail which increases considerably the stability of the apparatus.

The two lower planes 1 and 2 are formed each of two wings situated one on each side of the aeroplane body 7, while the top plane 3 is quite free of the top of the aeroplane body 7 to which it is fixed at its center by means of a pillar-like member 8.

It is to be understood that the respective positions of the planes 1, 2, 3 may vary from those shown. For instance, the top plane 3, instead of being set forwardly of the bottom plane 1, may be arranged in the same vertical line, the essential matter being that one of the three planes, preferably the mid-

dle plane 2, shall form a tail for the other two.

55

The improved aeroplane has the following advantages:—

From a constructional point of view, the triangular frames allow of dispensing with all cross-staying and of providing a very 60 light aeroplane.

They also allow of arranging the planes lozenge-fashion and thus considerably increase the stability of the aeroplane, the middle plane forming a tail for the other 65 two.

From an aero-dynamic point of view, the narrow wings of the improved aeroplane give:—

(1) a high degree of efficiency; the supporting power of the improved aeroplane being greater by 10 per cent. than that of a monoplane having the same stretch of wing and the same area:

(2) the displacement of the centers of pressure are very slight in the improved aeroplane, namely, about one-third of the displacement of a monoplane having the same stretch of wing and thrice the same depth of wing.

70

Having now described our invention what we claim as new and desire to secure by Letters Patent is:—

80

1. An aeroplane of the triplane type, comprising a single top supporting plane, a bottom plane made of two laterally spaced alining sections, a middle plane likewise made of two laterally spaced alining sections, a driven aeroplane body extending through the space between said sections of the middle 90 and bottom planes, a connection between said body and the plane structure, and a triangular frame on each side of the body, connecting the top plane with the sections of the middle and bottom planes on that side in 95 such a way that one of the planes forms a tail for the other two.

85

2. An aeroplane of the triplane type, comprising in combination a driven aeroplane body, a single top supporting plane, a bottom and a middle plane arranged on each side of the body, and a triangular frame on each side of the body, the apices of which frames connect together all of the planes in such a way that one of the planes forms a 105 tail for the other two.

100

105

3. An aeroplane of the triplane type comprising a single top supporting plane, a bottom plane made of two laterally spaced alining sections, a middle plane likewise made of two laterally spaced alining sections, a driven aeroplane body extending through the space between said sections of the middle and bottom planes, a pillar connecting said body with the top plane and comprising
5 10 a plurality of members converging up-

wardly both lengthwise and transversely of the body, and a triangular frame on each side of the body, connecting the top plane with the sections of the middle and bottom planes on that side in such a way that one 15 of the planes forms a tail for the other two.

In testimony whereof I have signed my name to this specification.

GUSTAVE DELAGE.
